ABSTRACT

A carburettor detergent comprises a compound formula $R-O-R^1-N.R^2.R^3$ where R is a hydrocarbyl group containing at least 20 carbon atoms, R^1 is a hydrocarbyl or amino substituted hydrocarbyl group and R^2 and R^3 are hydrogen or an alkyl group.

4 Claims, No Drawings

carburettor is rated visually for deposits and rated on an arbitrary 0 to 10 scale, 10 indicating a clean carburettor.

The following results were obtained.

of isobutylene, R¹ is a polymethylene group containing 2 to 6 carbon atoms interrupted by an imino group, and R² and R³, which may be the same or different are hydrogen atoms or alkyl groups.

Compound	Concen- tration (ppm)	% N	Rating
None	—	—	2.5-3
PIB - O CH ₂ CH ₂ NH CH ₂ CH ₂ NH ₂	140	0.84	7.5
PIB - O CH ₂ CH ₂ NH CH ₂ CH ₂ CH ₂ N CH ₃	130	0.97	7.5

We claim:

1. A fuel composition comprising gasoline and up to 1,000 parts per million of a carburettor detergent of the formula:

wherein R is a hydrocarbyl group containing from 20 to 500 carbon atoms and derived from the polymerization

2. A composition according to claim 1 wherein R² and R³, when alkyl groups, contain 1 to 4 carbon atoms.

3. A composition according to claim 1 which contains 50-200 parts per million of the carburetor detergent compound.

4. A composition according to claim 1 wherein R¹ is selected from the group consisting of —CH₂CH₂NH CH₂CH₂— and —CH₂CH₂CH₂NHCH₂CH₂CH₂—.
